B. D. WILLIS

MAKE BUSY SCHEME FOR TELEPHONE SYSTEMS

Filed Aug. 28, 1922

—Inventor—

Bernard D. Hillis

Chas. T. Candy, Atty:

UNITED STATES PATENT OFFICE.

BERNARD D. WILLIS, OF OAK PARK, ILLINOIS, ASSIGNOR TO AUTOMATIC ELECTRIC COMPANY, OF CHICAGO, ILLINOIS, A CORPORATION OF ILLINOIS.

MAKE-BUSY SCHEME FOR TELEPHONE SYSTEMS.

Application filed August 28, 1922. Serial No. 584,761.

To all whom it may concern:

Be it known that I, BERNARD D. WILLIS, a citizen of the United States of America, and a resident of Oak Park, Cook County, and State of Illinois, have invented certain new and useful Improvements in Make-Busy Schemes for Telephone Systems, of which the following is a specification.

The present invention relates to make busy schemes for telephone systems in general, but is more particularly applicable to make busy schemes for telephone systems in which primary and secondary trunking is used, and the principal object is the production of a new and improved arrangement for making busy all the idle secondary switches of a group as soon as all the trunks accessible thereto become busy.

So far as applicant knows, it has been the practice in primary and secondary trunking systems to use one chain relay per secondary trunk for making a secondary group busy when all the secondary trunks become busy. While this arrangement has proven fairly successful from an operating standpoint, it is desirable from an economical standpoint to reduce the equipment and to simplify the arrangement. This is done according to the present invention by providing one relay per group of trunks, which relay is normally short circuited by a ground potential which is placed on a common conductor by each of the switches to which the trunks accessible to a secondary group extend. This ground potential is removed by the switches in succession as they become busy and, when the last switch becomes busy, the shunt is finally removed from the common relay, whereupon the group is made busy.

According to another feature of the invention, the same principle is applied to a secondary group in which part of the trunks are individual to the group and other trunks are common to this group and to as many others as desired. In this case, the group make-busy relay is controlled from the individual trunks and a similar relay is controlled by the common trunks, and the relay of the common group maintains the make-busy relay shunted until the last common trunk becomes busy.

Another object is to arrange the selectors which are accessible to the secondary switches so that they control the shunting

ground with the addition of a minimum amount of equipment.

Referring now to the drawings, which comprise a single sheet, there is shown a line switch C individual to the line of substation A, and having access to the secondary switch D, which secondary switch, together with the others in the same group, has access to a certain number of trunks individual to that group, of which the trunk extending to the selector E is one. The switches of this group have access also to a plurality of common trunks of which the trunk extending to the selector E', which is denoted by the dotted rectangle bearing that reference character, is one.

The line switch C and the secondary switch D are of the well-known rotary type, in which the wipers have no normal position and move in a forward direction only, while the selectors such as E are of the well-known vertical and rotary type, and, accordingly, have 100 sets of bank contacts which are arranged in ten horizontal rows or levels.

The circuits of the switches C and D are well-known and likewise the circuits of the selectors such as E, with the exception of the addition of the lower contact of off normal spring 73 and the associated conductor and the improved make-busy jack J.

Perhaps the apparatus shown will be understood better in connection with its operation when a call is being extended therethrough.

When the receiver is removed at substation A, a circuit is closed over line conductors 11 and 12 for line relay 14 of the line switch C. Relay 14, upon energizing, places ground upon private normal conductor 10 at armature 20, thereby making the calling line busy, and closing a circuit for switching relay 13 and stepping magnet 15 in series, and at armature 19 connects test wiper 22 to the junction of switching relay 13 and stepping magnet 15. In case the trunk upon which the wipers are standing is idle, the connecting up of the test wiper has no particular function and switching relay 13 energizes immediately. Assuming the trunk to be busy, however, switching relay 13 is short circuited by the ground potential which is present on the test contact thereof, and the wipers 21-23, inclusive, are advanced in search of an idle trunk by the buzz-

2

zer-like action of stepping magnet 15, which operates through test wiper 22. When an idle trunk is reached, which trunk it will be assumed is the one extending to the secondary switch D, switching relay 13, being no longer short circuited, energizes in series with stepping magnet 15, stepping magnet 15 not energizing on account of the high resistance of switching relay 13. Upon energizing, switching relay 13 opens the test circuit and prepares the holding circuit at armature 17, and at armatures 16 and 18 disconnects line conductors 11 and 12 from the winding of line relay 14 and ground, and extends them by way of wipers 21 and 23, conductors 24 and 26, and armatures 30 and 33 to the winding of line relay 28 of the secondary switch D and ground, respectively. Line relay 28, upon energizing, places ground on release trunk conductor 25 at armature 36, thereby establishing the usual holding circuit for switching relay 13 of the line switch C before slow acting relay 14 has had time to deenergize. As a further result of the energization of relay 28, it closes a circuit for switching relay 27 and stepping magnet 29 in series at armature 35, and at armature 34 connects test wiper 38 to the junction of the switching relay and the stepping magnet. The secondary switch D now operates in the same manner as the line switch C to select an idle trunk, which trunk it will be assumed is the one comprising conductors 40-42, inclusive, and extending to the selector E. Switching relay 27, upon energizing, when the idle trunk is reached, extends release trunk conductor 25 through to test wiper 38 at armature 32; opens the test circuit and prepares the holding circuit for relay 27 at armature 31; and at armatures 30 and 33 disconnects conductors 24 and 26 from the winding of line relay 28 and ground, and extends them by way of wipers 37 and 39, conductors 40 and 42, and armatures 82 and 85 and their resting contacts to the windings of line relay 65 of selector E. Line relay 65, upon energizing, removes ground at one point from the common conductor 55, and closes a circuit for release relay 66 at armature 76, which circuit includes armature 84 and its resting contact and the normal contact of the jack J. Release relay 66, upon energizing, disconnects the resting contact of armature 76 from off normal spring 73 and prepares a circuit for vertical magnet 70 at armature 78, and at armature 77 places ground on release trunk conductor 41, thereby establishing the usual holding circuit for the switches C and D.

When the calling subscriber operates his calling device in accordance with the first digit in the desired number, line relay 65 is deenergized a corresponding number of times, and, upon each deenergization, closes

a circuit for vertical magnet 70 by way of armature 78 and its working contact and series relay 67. By the operation of vertical magnet 70, the switch wipers 86-88, inclusive, are raised opposite the desired level of bank contacts. Slow acting series relay 67 is maintained energized in series with vertical magnet 70 throughout the vertical movement and, in conjunction with the off normal contacts 74, which close upon the first vertical step, closes a circuit for stepping relay 68 by way of interrupter contacts 75. Stepping relay 68, upon energizing, closes a locking circuit for itself at armature 80 and at armature 81 prepares a circuit for rotary magnet 71.

At the end of the vertical movement, slow acting relay 67 deenergizes and closes the circuit of rotary magnet 71 at armature 79. Rotary magnet 71, upon energizing, advances the wipers 86-88, inclusive, into engagement with the first set of bank contacts in the level opposite which they are raised and, near the end of its stroke, opens the circuit of stepping relay 68. Stepping relay 68, upon deenergizing, opens the circuit of rotary magnet 71 at armature 81, whereupon rotary magnet 71 deenergizes and closes its interrupter contacts 75 again. In case the trunk terminating in the first set of bank contacts is idle, switching relay 69 energizes in series with stepping relay 68 at this time. Assuming the trunk to be busy, however, switching relay 69 is short circuited and relay 68, upon energizing, closes a circuit for rotary magnet 71, whereupon the switch wipers are advanced into engagement with the next set of bank contacts. This operation continues until an idle trunk is reached, which trunk it will be assumed is the one terminating in bank contacts 89-91, inclusive, whereupon switching relay 69, being no longer short circuited, energizes over the following circuit: From ground by way of the working contact of armature 77 and said armature, switching relay 69, off normal contacts 74, interrupter contacts 75, and stepping relay 68 to battery. Stepping relay 68 does not energize at this time, however, owing to the high resistance of switching relay 69. Switching relay 69, upon energizing, disconnects ground from armature 76 of line relay 65 at armature 84, thereby opening the circuit of release relay 66; opens the test circuit and prepares the holding circuit at armature 83; and at armatures 82 and 85 disconnects conductors 40 and 42 from relay 65 and extends them by way of wipers 86 and 88 and bank contacts 89 and 91 to the windings of the line relay of the switch to which the seized trunk extends. When this occurs, the line and release relays (not shown) of the seized trunk energize, whereupon the latter places ground upon the associated

release trunk conductor, thereby establishing the usual holding circuit for the switches C, D, and E before the release relay 66 has had time to deenergize.

6 The calling subscriber may now extend the connection on to the desired line in the usual manner and, when he replaces his receiver at the end of the conversation, ground is removed from the release trunk conductor 10 of the trunk seized by the selector E, whereupon the switching relays 18, 27, and 69 of the switches C, D, and E, respectively, deenergize. Switching relay 69, upon deenergizing, closes a circuit for release magnet 72 as follows: from ground by way of the normal contact of the jack J, resting contact of armature 84 and said armature, armature 76 and its resting contact, armature 78 and its resting contact, off normal 15 spring 73 and its upper contact, and release magnet 72 to battery. Upon the energization of release magnet 72, the shaft and wipers of the selector E are restored to normal position in the usual manner. When the shaft 20 of the selector E reaches normal position, it shifts the off normal springs, whereupon spring 73 opens the circuit of release magnet 72 and applies ground to conductor 55. The operation of the make-busy equipment will now be taken up a little more in detail. It was pointed out above that the selector E removes ground from conductor 25 55 upon being seized and replaces the ground when it becomes idle and is restored to normal. Assuming now that the ground potential is removed from conductor 55 by all of the selectors, such as E, individual to the group; conductor 55 remains grounded by armature 53 of relay 50 which is associated with the trunks which 30 are common to several secondary groups. Assuming further that the common trunks also become busy, ground is removed from conductor 51 by all the common selectors 35 such as E', whereupon relay 50 energizes in series with resistance 52 and removes ground from all the conductors such as 55 of the groups from which the common group of trunks is accessible. When this 40 occurs, relay 54 energizes in series with resistance 57 and makes all the idle secondary line switches in the group busy, the trunk extending to the switch D for example, being made busy through the resting contact 45 of armature 32 and said armature. 50

As soon as a trunk becomes available in either the common group or the individual group, the secondary group in question is rendered idle again. For example, if one 55 of the selectors such as E places ground on conductor 55, upon being restored to normal, relay 54 is short circuited and deenergizes, or if one of the selectors such as E' places ground on conductor 51 of the common group of trunks, relay 50 is short circuited

and, upon deenergizing, places ground on conductor 55, whereupon relay 54 deenergizes also.

In case it is desired to make a particular switch which is accessible to a secondary switch busy, it is necessary to do two things. One is to place ground on the associated release trunk conductor and the other is to remove ground at that point from the common make-busy conductor. In the case of 70 the selector E, this is accomplished by inserting a piece of conducting material of the proper size and shape, such as P, between the springs of the jack J. This applies ground to release trunk conductor 41 through the inserted conductor and removes ground from conductor 55 by the lower spring of the jack J moving out of engagement with its normal contact. 80

What is claimed is:

1. In a trunking system, a group of trunks, a switch having access thereto, a conductor common to said group maintained at a certain potential at each of said trunks, means for taking said trunks for use, means responsive to the taking for use of each of said trunks for removing said certain potential from said conductor at one point, and means responsive to the removal of said certain potential at the last trunk to be taken for use for rendering said switch non-selectable. 90

2. In a trunking system a first group of switches, a first group of trunks accessible thereto, a second group of switches, a second group of trunks accessible to both said groups of switches in common, a first and a second conductor common to said first and said second groups of trunks, respectively, each of said conductors being maintained at a certain potential by each of the trunks in the group to which it is common, means controlled over said second conductor for maintaining said first conductor at said certain potential at still another point, means for taking said trunks for use, means responsive to the taking for use of each of said trunks for removing said certain potential from the associated common conductor at one point, means responsive to the removal of said potential from said second conductor at all points for removing said potential from said first conductor at said other point, and means responsive to the removal of said certain potential from said first conductor at all points for rendering said first group of switches non-selectable. 100 105 110 115

3. In a telephone system, a first group of switches, a second group of switches accessible to said first group, each of the switches in said second group having line, holding, and release relays, and normally closed off normal contacts, normally closed contacts on each of said relays, a conductor common to said second group of switches and being 120 125 130

- maintained at a ground potential by each of said switches through said normally closed contacts on each of the relays named and said off normal contacts in series, means for taking each of said switches for use, means effective while one of said switches is in use for removing the ground potential from said common conductor at that point by maintaining open one or more of said normally closed contacts, and means controlled by the removal of said ground potential from said conductor at all points for rendering said first group of switches non-selectable.
4. In a trunking system, a group of trunks, a switch having access thereto, a conductor common to said group being maintained at a certain potential at each of said trunks, means for taking said trunks for use, means responsive to the taking for use of each of said trunks for removing said certain potential from said conductor at one point, means responsive to the removal of said certain potential at the last trunk to be taken for use for rendering said switch non-selectable, a jack for each of said trunks, and means responsive to plugging into one of said jacks for rendering the associated trunk non-selectable and for removing said certain potential from said conductor at that point.
5. The combination, with a group of automatic switches, of a guarding circuit including a relay and a source of current, a pair of contacts at each switch for short-circuiting said relay, and means in each switch for opening the associated contacts when the switch is operated.
6. The combination, with two groups of automatic switches, of a guarding circuit for the first group of switches controlled jointly by the switches in the second group, said circuit including a relay and a source of current, contacts on a switch in the second group for maintaining said relay short circuited while the switch is in normal position, and similar contacts on each of the other switches in the second group.
7. The combination, with a group of switches, of a relay, and means for operating said relay only when all said switches

are in use, said means comprising a closed circuit for said relay, and means in each switch effective while the switch is idle for maintaining said relay short circuited.

8. In a telephone system, a group of lines, an electro-magnet common to said lines, a circuit for said magnet including a source of current, a pair of contacts individual to each line, circuits over which all said pairs of contacts are connected in parallel with each other and in shunt of said relay, and means for opening each pair of contacts when the associated line is in use.

9. In a telephone system, a group of lines, an electro-magnet common to said lines, a circuit for said magnet including a source of current, a pair of contacts individual to each line, circuits over which all said pairs of contacts are connected in parallel with each other and in shunt of said relay, means for opening each pair of contacts when the associated line is in use, and a resistance included in said circuit to prevent excessive current flow while said magnet is short-circuited.

10. In a telephone system, an automatic switch, a guarding circuit common to said switch and other similar switches, a line relay in said switch having a pair of contacts, an operating circuit for the switch over which said contacts transmit impulses when the switch is in use, and a branch of said guarding circuit on which said contacts maintain a potential while the switch is idle.

11. In a telephone system, an automatic switch, a guarding circuit having a branch incoming to said switch, a release magnet for said switch, a local switch conductor connected to a source of current, means for connecting said conductor to said magnet to release said switch, and means responsive to the restoration of said switch for disconnecting said conductor from said magnet and for connecting it to the said branch of said guarding circuit.

In witness whereof, I hereunto subscribe my name this 25th day of August, A. D., 1922.

BERNARD D. WILLIS.

DISCLAIMER.

1,537,326.—*Bernard D. Willis, Oak Park, Ill. MAKE-BUSY SCHEME FOR TELEPHONE SYSTEMS.* Patent dated May 12, 1925. Disclaimer filed May 20, 1926, by the assignee, *Automatic Electric Inc.*

Hereby enters a disclaimer to claims 1, 5, 7, 8, and 9 in said specification, which are in the following words, to wit:

“1. In a trunking system, a group of trunks, a switch having access thereto, a conductor common to said group maintained at a certain potential at each of said trunks, means for taking said trunks for use, means responsive to the taking for use of each of said trunks for removing said certain potential from said conductor at one point, and means responsive to the removal of said certain potential at the last trunk to be taken for use for rendering said switch non-selectable.

“5. The combination, with a group of automatic switches, of a guarding circuit including a relay and a source of current, a pair of contacts at each switch for short-circuiting said relay, and means in each switch for opening the associated contacts when the switch is operated.

“7. The combination, with a group of switches, of a relay, and means for operating said relay only when all said switches are in use, said means comprising a closed circuit for said relay, and means in each switch effective while the switch is idle for maintaining said relay short circuited.

“8. In a telephone system, a group of lines, an electro-magnet common to said lines, a circuit for said magnet including a source of current, a pair of contacts individual to each line, circuits over which all said pairs of contacts are connected in parallel with each other and in shunt of said relay, and means for opening each pair of contacts when the associated line is in use.

“9. In a telephone system, a group of lines, an electro-magnet common to said lines, a circuit for said magnet including a source of current, a pair of contacts individual to each line, circuits over which all said pairs of contacts are connected in parallel with each other and in shunt of said relay, means for opening each pair of contacts when the associated line is in use, and a resistance included in said circuit to prevent excessive current flow while said magnet is short-circuited.”
